2 Claims. (Cl. 205—46)

This invention relates to a package for microphones, particularly for amateur microphones for tape recorders, comprising an at least partly transparent enclosure which accommodates the microphone.

Such packages have been used for a considerable time for a very wide range of articles. These packages consisted merely of a box, which was at least partly made from transparent thermoplastic material. In packages for articles which consisted of a main article and accessories, the boxlike housings of transparent material were internally divided to provide small compartments for accommodating the accessories received therein. Such packages have been provided, for instance, for some exposure meters for amateur photographers. An elongated lower portion of a box was divided by a transverse partition into a larger compartment for the exposure meter itself and a smaller compartment for the carrying chain secured to the meter. A cover of the usual shape and consisting also of transparent material permits closing of the box.

Packages for amateur microphones consist in most cases of cartons or sometimes of plastic boxes similar to the packages for photographic exposure meters. The cable connected to the microphone is rolled up and accommodated in the package besides the microphone.

In this package, which is used in most cases by the amateur also for storing the microphone, the microphone is mostly rolled up randomly, generally becoming tangled. The wire can be disentangled only with difficulty and often kinks are formed in the cable. Such treatment will lead sooner or later to damage to the cable, which may fail just at a decisive moment.

It is an object of the invention to eliminate such defects and to provide a package designed to enable an orderly accommodation of the microphone cable and to serve also as an auxiliary support for the microphone, if desired. The essential feature of the package according to the invention resides in that the base portion of the package, which accommodates the microphone, is similar to a bobbin having two parallel flanges and a central core, which has an opening in which the microphone can be inserted whereas the microphone cable can be wound around the core between the aforementioned flanges, the transparent cover of the package having side walls which close the space between the two flanges when the cover is in position.

The above and other objects, features and advantages of the present invention will become more readily apparent from the following description, reference being made to the accompanying drawing in which

FIG. 1 is a perspective view of the base of a microphone package embodying the present invention, with the microphone, cable and plug removed;

FIG. 2 is a vertical cross-sectional view through the package of FIG. 1 showing the cover thereof co-operating with the base;

FIG. 3 is a cross-sectional view similar to FIG. 2 of a modified case wherein the cover member bears frictionally against the peripheries of the upper and lower flanges of the base;

FIG. 4 is another sectional view similar to FIG. 2 showing a modified microphone package, with the microphone, cable and plug removed, wherein the flanges of

2

the base part are provided with inwardly turned ridges for retaining the microphone cable in the compartment formed between the two flanges, the closed peripheral wall of the cover of this embodiment, as in the embodiment of FIG. 3, having a generatrix parallel to a line connecting corresponding locations of the flange peripheries; and

FIG. 5 is a vertical cross-sectional view through the base portion of a microphone package with the cover removed showing the pivotal support member for maintaining the microphone in an elevated position and the aperture of the base plate, whereby the microphone can be lifted to shift the support member into its operable position.

As is apparent from FIG. 1, the lower part or base of the package consists of a bobbinlike body and comprises two horizontal flanges 1 and 2. These two flanges 1 and 2 extend outwardly from the upper and lower peripheral edges of an annular core 3 whose interior forms a compartment 15 having a bottom plate 5. This compartment 15 is suitably designed to conform to the shape of the microphone, shown at 16 in FIG. 5, and may be of irregular contour. In the drawing, the chamber is shown to be of prismatic shape, for the sake of simplicity. A slot 6 serves for passing the microphone cable 9 out of the central core 3. It is not essential to dispose this slot in the position shown in FIG. 1. The position of the slot will depend on the design of the microphone because the cable may, alternatively, extend laterally out of the opening. When the microphone has been inserted into the compartment 5, the microphone cable passed through the slots 6 is wound around the core 3 in the winding space provided between the flanges 1 and 2. If the two flanges were closely spaced, it would not be possible to accommodate the microphone plug 10, which is generally much thicker than the microphone cable, in the winding space for the cable. For this reason the upper flange 1 is formed at one edge, preferably at a corner, with a cut-away portion or recess 7, the size of which corresponds to the dimensions of the plug 10.

FIGS. 2 and 3 are transverse sectional views showing different embodiments of the package according to the invention. In the embodiment shown in FIG. 2, the case has the configuration of a rectangular prism. To provide a stop for the cover, which consists suitably of transparent material, when it is mounted on the base part of the package, the lower flange 2 of the bobbin projects beyond the upper flange 1 on all sides approximately by the wall thickness of the cover 4. Alternatively, the package may be designed as is shown in FIG. 3, namely, with oblique side parts. The cover 4 has a top held elevated above the base 1-3 by the removable engagement of the outer edges of flanges 1 and 2 with an intermediate zone and with the bottom edge of the downwardly diverging peripheral cover wall. In this case a stop for the cover is not essential for a stop as shown in FIG. 2 may be provided. Alternatively, the stop may be provided on the cover 4 to engage the upper flange 1. If the stop is provided on the cover 4, the flanges in the embodiment shown in FIG. 2 may be of equal size. This may result in a simplification of the production.

In FIG. 2 the bobbin-shaped part of the package is assembled, e.g. by bonding, from separate parts, namely, the two flanges 1, 2 and the core 3. Where appropriate machinery is available the entire base part of the package consisting of the two flanges 1, 2 and the core 3 may be made in one piece.

An embodiment of the package according to the invention which is particularly desirable and of pleasing appearance is shown in FIG. 4. The bottom flange 2 has an upturned rim 3, which serves for retaining the cover 4 and reducing the size of the gap between the two

flanges 1 and 2 to some extent so that at least during simple movements of the bottom part of the case, such as placing it on or removing it from a support, the microphone cable and the plug cannot fall out. To assist this effect, the upper flange 2 may also be provided with such a rim portion 8', as is shown in the left-hand half of FIG. 4.

The material from which the parts of the package are made consists suitably of thermoplastic material. In order to conceal the turns of the microphone cable, which are in most cases irregular, the base part of the package, which accommodates the microphone and the cable with plug, is suitably made of non-transparent, colored material. On the other hand, the cover 4 should enable a view of the packaged article, i.e., the microphone, and for this reason is made from transparent material.

Some amateurs do not have a separate stand for the microphone. For this reason many microphones are supplied with a small support, e.g., in the form of a base. The need for such a base is eliminated by the package according to the invention if a hinged stay 11 (FIG. 5), which can preferably be sunk in a wall part, is provided in the compartment 15 of the core 3. In this case the base plate 5 of the package constitutes a support which has a high stability and enables a much more reliable mounting of the microphone 16 than the small base or stand supplied in most cases with the microphone proper. As shown in FIG. 5, the microphone 16 is movable in the compartment 15 between a raised position (full lines) and a withdrawn position (dot-dash lines). The raising of the microphone into its full-line position is facilitated by the provision of an aperture 17 in base plate 5.

In conclusion it may be stated that the package according to the invention for microphones or the like has an extremely pleasing appearance, is most suitable for display and owing to the design of the base part enables also a quick and simple packaging. Even an amateur who is compelled to stow away the microphone after each recording of sound is provided by the package according to the invention with an excellent device for the proper and protected keeping of his microphone. This device provides at the same time a captive holder, in which the microphone can be arranged in position for use.

What I claim is:

1. A package comprising a microphone and an enclosure therefor composed of a base and a cover; said base including an annular upright core forming an up-

wardly open microphone-receiving compartment, a bottom plate for said compartment rigid with said core, a first flange projecting horizontally outwardly from the lower peripheral edge of said core in the plane of said base plate, and a second flange projecting horizontally outwardly from the upper peripheral edge of said core for a lesser distance than said first flange and defining therewith an annular gap, said core and upper flange being provided with a slot interconnecting said compartment and said gap; said microphone resting on said bottom plate in said compartment and being provided with a cord passing outwardly through said slot into said gap, the greater part of said cord being wound about said core in said gap; said cover having a downwardly diverging peripheral wall removably engaging said base along the outer edges of said flanges, said peripheral wall having a bottom edge in contact with the outer edge of said first flange and having a zone below its top in contact with the outer edge of said second flange whereby said top is held elevated above said core and second flange.

2. A package as defined in claim 1 wherein said microphone is movable between a withdrawn position on said plate and a raised position in which it projects upwardly from said compartment, said bottom plate having an aperture facilitating the raising of said microphone from its withdrawn position, said base being provided with hinged stay means for supporting said microphone in its raised position.
